United States Patent

Des. 240,542

Patented July 13, 1976

240,542

SMOKING PIPE

Joseph E. Murray, Jr., 27 Alpine St.,
Malden, Mass. 02148

Filed Jan. 15, 1975, Ser. No. 541,289

Term of patent 14 years

Int. Cl. D27—02

U.S. Cl. D27—3

FIG. 1

FIG. 2

FIG. 3

FIG. 1 is a perspective view of a smoking pipe showing my new design;

FIG. 2 is an elevational view of the side opposite that shown in FIG. 1; and

FIG. 3 is a top plan view thereof, the bottom of the body being flat and unornamented.

I claim:

The ornamental design for a smoking pipe, as shown and described.
